UNITED STATES PATENT OFFICE.

HARRY W. SMITH, OF AKRON, OHIO, ASSIGNOR OF ONE-FOURTH TO GEORGE J. RENNER, OF YOUNGSTOWN, OHIO, AND ONE-FOURTH TO EARNEST C. DEIBEL, OF AKRON, OHIO.

HANDLE GRIP.

Application filed December 2, 1920. Serial No. 427,818.

To all whom it may concern:

Be it known that I, HARRY W. SMITH, a citizen of the United States, residing at Akron, in the county of Summit and State of Ohio, have invented new and useful Improvements in Handle Grips, of which the following is a specification.

This invention relates to improvements in handles and particularly to improvements in 10 grips for such handles.

It is an object of the invention to provide a new and improved handle which may be grasped firmly and easily held without turning or slipping.

15 A further object is to provide a durable cover of simple, economical construction, which is adapted to be placed on the handles of golf clubs, baseball bats, tennis rackets, fishing rods or any instrument or device 20 whereby a non-slipping grip may be easily maintained, and to thus provide an instrument which may be used with great accuracy and precision.

25 A further object is to provide a handle which will embody an accomplishment of the above objects and which may be used without injury or discomfort to the hands.

An important object is to provide a rubber cover for handles comprising an integral 30 body having an outer wearing portion of vulcanized rubber and an inner sticky plastic portion whereby the same may be adhesively secured to the handles of golf clubs and the like and to provide means whereby 35 said plastic portion will be protected in storage or transit and preserved in a plastic state until ready for use.

The above objects are accomplished and 40 additional ends are attained by the novel construction, combination and arrangement of parts herein described and illustrated in the accompanying drawing which forms a part hereof and in which I have shown a preferred embodiment of the invention, it being 45 understood that the invention is capable of various adaptations and that variations in form or material may be made or substitutions resorted to which come within the scope of the claims hereunto appended.

50 In the drawing, in which similar characters of reference are employed to designate corresponding parts throughout the several views and in which:—

Figure 1 is a side elevation of a golf club

equipped with a non-slipping handle grip 55 constructed in accordance with this invention.

Figure 2 is a perspective view of a roll 60 of the material employed in carrying out this invention.

Figure 3 is a longitudinal sectional view 65 of the end portion of a handle constructed in accordance with this invention taken as indicated by the lines 3—3 of Figure 4.

Figure 4 is a side elevation of a handle 70 equipped with my improved grip.

Figure 5 is a transverse sectional view of 75 the grip employed in carrying out the invention taken as indicated by the lines 5—5 of Figure 2.

In the accompanying drawing, I have 80 shown the invention as applied to a golf club to which an embodiment thereof may be used to a great advantage. The numeral 5 is used generally to denote an ordinary wooden handle and the numeral 6 indicates a layer of 85 rubberized textile fabric or other relatively inextensible, non-absorbent material which is wound around the handle under tension and cemented thereto so as to form a relatively inelastic base. The numeral 7 indicates 90 my improved grip strip which is wound spirally around the handle 5 upon the base 6 and is cemented thereto. The strip 7 is composed of rubber or similar elastic material and is provided throughout its length with a plurality of closely spaced regularly recurring openings or perforations 8. The strip 7 has a main wearing portion which is 95 formed of vulcanized rubber and a sticky 100 plastic portion 9 which is an integral part of the strip 7 and extends over the entire attaching face thereof. The numeral 10 is used to denote a protective strip of muslin or other relative non-adhesive material with 105 which the plastic surface 9 is covered. The non-adhesive strip or lining 10 serves to protect the attaching surface 9, preserves it in a plastic state, and provides a more convenient and more attractive product. The strip 7 may be wound around the base 6 with its edges in parallel spaced relation, as shown in Figure 3, thus providing a helically disposed groove 11.

My improved grip may be attached directly to the handle by means of the plastic face 9 or the handle may be first coated with rubber cement or other suitable adhesive. I

prefer first to wind the rubber impregnated strips 6 about the handle to produce a grip of the desired size, and to coat the base layer 6 thus formed with rubber cement. The lining strip 10 is removed from the perforated strip 7 and the same is wound spirally around the base layer 6 with the plastic face 9 in contact with the cemented surface of the base layer.

- 10 The provision of the plastic attaching face 9 is very convenient and provides an extremely effective and reliable means whereby the non-slipping grip strip may be secured to a handle. The strip 7 when properly applied to a handle will last indefinitely, inasmuch as the base 6 is rubberized and it is consequently water-proof and non-absorbent and the rubber cement or other adhesive used to attach the same to the handle can-
15 not be effected by moisture and a lasting union is secured between the cover 7 and the base 6.

When taken in a firm grasp, portions of the hand directly over each opening 8 will bulge slightly therein and contact with the edges thereof, thus providing an extremely effective non-slipping grip. The openings 8 are closed at the bottom by means of the rubberized material 6, thus forming a plurality of cups out of which a portion of the air is forced when a grip is seized by the hand and a partial vacuum is created therein which aids materially in preventing an unintentional turning or slipping movement of an instrument equipped in accordance with my invention.

In actual use, on a golf club, it has been found that the non-slipping qualities of my improved grip are not effected by moisture 40 or by changes in temperature and that a club equipped as herein set forth may be used to great advantage regardless of climatic or weather conditions. In contrast with ordinary grips, I have provided a grip 45 which when placed on the handle of a golf club will permit the same to be used when wet or with wet hands, without danger of slipping and I have therefore provided means whereby a club so equipped may be

used with great accuracy and precision even 50 under the most unfavorable conditions.

While I have shown and described the strip 7 as provided with a plurality of circular openings 8, it is to be understood that the same may be formed of any desired 55 shape and while I have provided a non-absorbent relatively, inextensible base, the strip 7 may be used without said base and attached by means of its plastic face directly to the handle.

Having thus described my invention what I claim as new and desire to secure by Letters Patent is:-

1. A non-slipping cover for golf club grips and the like comprising a flat strip of elastic 65 material provided on the attaching face thereof with an integrally formed backing of plastic elastic material, said strip provided throughout its length with a plurality of regularly recurring openings.

2. A non-slipping cover for golf club grips, comprising, a flat strip of rubber adapted to be wound spirally therearound, said strip including a wearing portion of vulcanized rubber and an attaching portion 75 of sticky unvulcanized rubber.

3. A non-slipping cover for golf club grips, comprising a flat strip of rubber adapted to be wound spirally thereabout, said strip including a wearing portion of vulcanized rubber and an attaching portion of plastic, sticky, unvulcanized rubber and removable means to protect and preserve said attaching portion until ready for use.

4. A non-slipping grip for golf clubs comprising a flat strip of rubber adapted to be wound spirally thereabout, said strip including main body portion of vulcanized rubber and an attaching portion of unvulcanized rubber, said strip provided throughout its 90 length with a plurality of spaced, regularly recurring openings which extend through both the wearing portion and the attaching portion and removable means to protect and preserve said portion until ready for use.

In testimony whereof I have hereunto set my hand.

HARRY W. SMITH.
